(57) **CLAIM**

The ornamental design for a headphone cover with arm guard, as shown and described.

DESCRIPTION

FIG. 1 is a perspective and environmental view of a headphone cover with arm guard according to the present invention illustrated as being connected to headphones and being worn by a user.

FIG. 2 is a perspective and environmental view of a headphone cover with arm guard according to the present invention illustrated as being connected to headphones.

FIG. 3 is a front elevation and environmental view of the headphone cover with arm guard shown in FIG. 2 and illustrated as being connected to headphones.

FIG. 4 is a rear elevation and environmental view of the headphone cover with arm guard shown in FIG. 2 and illustrated as being connected to headphones.

FIG. 5 is a side elevation and environmental view of the headphone cover with arm guard shown in FIG. 2 and illustrated as being connected to headphones.

FIG. 6 is another side elevation and environmental view of the headphone cover with arm guard shown in FIG. 2 and illustrated as being connected to headphones.

FIG. 7 is a top plan and environmental view of the headphone cover with arm guard shown in FIG. 2 and illustrated as being connected to headphones.

FIG. 8 is a bottom plan and environmental view of the headphone cover with arm guard shown in FIG. 2 and illustrated as being connected to headphones.

FIG. 9 is a perspective view of a headphone cover with arm guard according to the present invention.

FIG. 10 is a side elevation view of the headphone cover with arm guard illustrated in FIG. 9.

FIG. 11 is another side elevation view of the headphone cover with arm guard illustrated in FIG. 9.

FIG. 12 is a rear elevation view of the headphone cover with arm guard illustrated in FIG. 9.

FIG. 13 is front elevation view of the headphone cover with arm guard illustrated in FIG. 9.

FIG. 14 is a top plan view of the headphone cover with arm guard illustrated in FIG. 9; and,

FIG. 15 is bottom plan view of the headphone cover with arm guard illustrated in FIG. 9.

The broken lines in FIGS. 1-8 depict headphones having a connected microphone, and a user wearing the headphones having a connected microphone that do not form a claimed feature of the present invention.

1 Claim, 10 Drawing Sheets
